Specification for Design.

Patented Oct. 15, 1912.

Application filed November 18, 1911. Serial No. 661,181. Term of patent 7 years.

To all whom it may concern:

Be it known that I, LINDSLEY SCHEPMOES, a citizen of the United States, residing at Hasbrouck Heights, county of Bergen, and State of New Jersey, have invented a new, original, and ornamental Design for Deck-Lamp Fixtures, of which the following is a specification.

The nature of my design is fully illustrated in the accompanying drawing, to which reference is made, and which illustrates the design in elevation.

My design comprises a translucent globe having continuous walls curving from a central point and terminating at substantially equal distances therefrom, the walls

being provided with prismatic portions radiating from the central point, and a surrounding beading of prisms adjacent their terminal portions, the whole providing a substantially semi-globular structure generally circular in cross section, generally convex in external appearance and having the contour and relative proportion of parts shown.

I claim:

The ornamental design for a deck lamp fixture as shown and described.

LINDSLEY SCHEPMOES.
